US0D1085621S

(12) **United States Design Patent** (10) **Patent No.:** **US D1,085,621 S**
(45) **Date of Patent:** **** Jul. 22, 2025**

(54) **MECHANIC CREEPER MAT**

(71) Applicant: **Chenglei Wan**, Changzhou (CN)

(72) Inventor: **Chenglei Wan**, Changzhou (CN)

(**) Term: **15 Years**

(21) Appl. No.: **29/910,635**

(22) Filed: **Aug. 22, 2023**

(51) **LOC (15) Cl.** **12-02**

(52) **U.S. Cl.**

USPC **D34/27; D34/23**

(58) **Field of Classification Search**

USPC D34/12, 14, 23, 27, 28; D12/128, 133;
D29/124

CPC B25H 3/00; B25H 5/00
